UNITED STATES PATENT OFFICE

HEINRICH WISMER, OF ZURICH, SWITZERLAND

CIRCULAR LOOM FOR MANUFACTURING HATS AND THE LIKE

Application filed December 26, 1929, Serial No. 416,638, and in Germany February 1, 1929.

In a known circular loom, an increase in the number of warp threads used in the weaving has to be effected by unwinding fresh warp threads from the warp bobbin by hand and introducing them into the fabric again by hand. No sort of mechanical appliance for bringing in the warp threads is provided in this known loom or is applicable thereto.

In the circular loom according to the present invention, the adding of the new warp threads is effected mechanically and quite automatically, as a result of which not only is the quantitative output of the machine increased tenfold, but a thoroughly uniform and positive introduction is also obtained. In the case of the known circular loom mentioned above, the increase in the number of warp threads by hand could only be effected according to the judgement of the eye, so that closer and less close spaces occurred in the fabric.

In the circular loom according to the present invention, moreover, the warp threads do not have to be cut off and re-assembled by hand as in the case of the earlier constructions, for the purpose of producing a new formation, but always remain tensioned, and, after the termination of one woven article, are automatically assembled again by a mechanical device such as a gripper, so that hat-shaped articles can be manufactured in uninterrupted sequence by a completely automatic operation. For the conveyance of the chain of closed hollow fabrics there preferably serves a conveying device, which seizes it on both sides throughout the length that is being conveyed and accompanies it.

With the present circular loom the following advantages are obtained: The individual warp threads are independent of one another, as contrasted with the otherwise usual rolling upon a common warp beam; automatic resumption of the operation after completion of a woven article; a fixed path, offering but little friction, for the shuttle, and a positive and powerful drive of the latter, in which the very variable tension ratios (variable number of warp threads) and the unwieldiness of the raw materials applied (bast fibres and straw substitute) are allowed for.

The invention is diagrammatically illustrated in one constructional example in the accompanying drawings, in which

Figure 1 is a plan view of the circular loom.

Fig. 2 is an axial sectional elevation thereof.

Fig. 3^a shows a shuttle in end elevation, and means to drive the same.

Fig. 3^b shows the same in side elevation.

Fig. 4^a is a sectional view on line A—B of Fig. 4^b, showing the means for gradually raising the warp carriers.

Fig. 4^b shows the same in side elevation.

Fig. 5 is a side elevation of means for pressing the fabric against the mold, the means being shown in approach or closed position.

Fig. 6 is a plan view of the mold and of the said means, the latter being shown in open or expanded position.

Fig. 7 is a side elevation, similar to Fig. 5, showing the said means in open or expanded position, as in Fig. 6.

In these drawings, 1 is a stationary hollow cylinder with a foot and an upper inwardly directed flange 2, on which hollow cylinder are supported the bobbins 3 with the outer warp threads. 4 is a short rotatable hollow cylinder with upper and lower flanges 5 and 6, which cylinder carries the bobbins 7 for the inner warp threads and is set in slow rotation by means of a hollow shaft 4¹ and a worm drive 4². The warp threads pass from bobbins 3 and 7 through eyes 3^a and 7^a to the tips of warp carriers 8 and 9 square in cross-section.

The warp carriers 8 and 9 are bent inwards at right angles at the lower end and engage in oppositely inclined closed guiding grooves 11 and 12 provided on a rotary disc 10. A driving shaft 13 and a bevel drive 14 impart to the rotary disc 10 a revolving movement, whereby the warp carriers 8 and 9 are raised and lowered for the purpose of forming the shed.

The manufacture of circular, flat or hollow fabrics contemplated requires a gradual increase in the number of warp threads employed, in order that a uniform filling of the surface with warp threads may be obtained. In the loom illustrated, at the commence-

ment of the weaving, all the warp threads in the centre of the loom are laid upon a vertically displaceable mold 15¹, carried by the rod 15. Most of these threads, however, remain in the lowest position (Fig. 4^b) and do not participate in the weaving. Only gradually, that is, with the progressive increase in the circumference of the circular fabric that is being produced, do more and more warp threads come into use. The gradual raising of the mold shaft 15 is effected by a rotatable cam disc 15².

This increase in the number of warp threads employed is obtained owing to the fact that the bent ends 16 of the warp carriers 8 and 9 are of unequal length, as described more fully hereafter. Each of the inclined guiding grooves 11 and 12 has a gap 17 in the lower guiding flange (Fig. 4^a and 4^b) at the place where they begin to ascend again, which gap is filled up by a horizontally movable slider 18. The bent ends of the warp carriers are gradually increased in length; so that as the gap 17 is closed the number of warp carriers called into operation is progressively increased. These sliders 18, are displaceable forwards by means of non-circular discs not shown, are put rather far back at the commencement of the work, most of the warp carriers 8, 9 remain unmoved in the lowest position when the gap 17 revolves past them, and only a few of the warp carriers 8 and 9, with particularly long ends 16, are carried along by the slider 18 and supplied to the guiding groove 12.

Each of the sliders 18, slowly rotating in the direction of the arrow P (Fig. 4) together with the disc 10 gradually takes with it warp carriers with shorter and shorter ends 16, until all the warp carriers are taking part in the shed formation. The gap 17 permits the carriers not taken up by the slider 18 to pass. After the completion of a woven article each slider 18 quickly goes back again and the initial condition is reproduced. The shuttles 19 and 20 carry weft bobbins 22 and revolve upon a roller track formed of individual rollers 23 carried by rods 21 and 22. The advancing movement of the shuttles 19 and 20 is obtained by the fact that upon the latter is fitted a laterally inclined plate 24, upon which the warp carriers 8 and 9, positively lowered by the guiding grooves 11 and 12, press by means of a small roller 25. The lateral component of this pressure effects the forward movement of the shuttle.

For the purpose of obtaining a better covering of the unit of area with a definite number of warp threads the latter are placed not exactly radially but slightly tangentially to the margin of the fabric. This result has been obtained for example in the circular loom according to German Patent No. 369,761 by the slow rotation of the two warp

thread circles in opposite directions. It has now been discovered that the rotation of a single warp thread circle, the inner one for instance, produces exactly the same result. This latter method of working, here provided, brings with it important advantages, namely in the first place quite a considerable structural simplification, and in the second place the possibility of employing, for the outer warp thread circle which is now stationary, large warp bobbins fitted upon a stationary bobbin creel.

If the circular loom, instead of being employed for the manufacture of disc-shaped fabrics, is employed for the manufacture of circular hollow fabrics, hats for example, the mold 15¹ carried by the vertical rod 15 is fitted, which serves as a support for the fabric. This mold is slowly raised by the above-mentioned non-circular disc 15², so that the weaving zone is located at a constant level notwithstanding the progressive formation of the fabric.

In order that the fabric may fit snugly to the mold 15¹ the latter is loosely embraced by a tongs-like auxiliary appliance 26, 27, 28, 29 (Figs. 5, 6 and 7). These tongs, consisting of two semi-circular limbs 26 and 28 and of two carrying arms 27 and 29, moved from above by eccentrics, not shown, are closed (Fig. 5) at the commencement of the weaving work, when the mold 15¹ is lowered, then gradually open (Figs. 6 and 7) during the gradual raising of the mold 15¹, and finally allow the finished woven article to pass through, whereupon they close again, immediately after the lowering of the mold 15¹, for the purpose of assembling all the warp threads into one group. At the same time the finished woven article 30 is drawn upwards by an intermittently moving conveyor device hereinafter described.

The finished fabrics form an uninterrupted chain which is guided forward between two belt conveyors 31 and 32. It is possible however to employ other conveying means.

From the above account it will be evident that two weft threads are introduced into the shed at the same time, so that each weft thread always assumes the same shed position, that is to say, one weft thread in the shed position with the outer warp threads at the top and the inner warp threads underneath (Fig. 2 on the left) and one weft thread in the shed position with the outer warp threads underneath and the inner warp threads above (Fig. 2 on the right). From this it follows that the output is doubled. Contact of the warp threads during the revolving of the shuttles is prevented, and consequently tearing away of warp threads is precluded.

Instead of keeping the warp carriers or healds that are not participating in the shed formation in the lowest position, they may

alternatively be kept in the highest position, in which case by gradually pushing back the slider, a corresponding lowering of the warp thread carriers takes place, corresponding to 5 the different lengths of the bent portions of the warp carriers in the lifting device, for the purpose of shed formation.

In order that a sufficient number of driving warp carriers for the forward movement of 10 the shuttle may be present at the commencement of the weaving, there may be provided between the warp carriers that are still stationary special driving members which participate in the shed movement from the outset 15 but carry no warp threads.

What I claim is:—

1. A circular loom for the continuous and automatic manufacture of hats and hat-like articles, comprising warp carriers having 20 their lower ends bent, the bent portions at the lower ends of different warp carriers being of different lengths, a rotatable lifting device adapted to engage with the bent lower ends of the warp carriers and thereby to raise 25 the said warp carriers out of their lowest position for the formation of the shed, the rotatable lifting device being formed at its lowest point with a gap adapted to cause the 30 lifting device to fail to engage some of the warp carriers with shorter bent lower ends, and means for gradually closing the said gap and thereby progressively increasing the 35 number of warp threads participating in the weaving operation.

2. A circular loom for the continuous and automatic manufacture of hats and hat-like articles, comprising warp carriers having their lower ends bent, the bent portions at the lower ends of different warp carriers being of different lengths, a rotatable lifting device adapted to engage with the bent lower ends of the warp carriers and thereby to raise 40 the said warp carriers out of their lowest position for the formation of the shed, the rotatable lifting device being formed at its lowest point with a gap adapted to cause the lifting device to fail to engage some of the warp carriers with shorter bent lower ends, means for gradually closing the said gap and thereby progressively increasing the number of warp threads participating in the weaving 45 operation, a ring of columns, a roller rotatably mounted at the top of each column to form a circular roller track, and a shuttle resting upon the said roller track.

3. A circular loom for the continuous and automatic manufacture of hats and hat-like articles, comprising an outer ring of stationary warp carriers having their lower ends bent, a slowly revolving inner ring of warp carriers having their lower ends bent, the bent portions at the lower ends of different warp carriers being of different lengths, a 50 rotatable lifting device adapted to engage

with the bent lower ends of the warp carriers and thereby to raise the said warp carriers out of their lowest position for the formation of the shed, the warp threads from the moving warp carriers being laid spirally and the warp threads from the stationary warp carriers being laid radially, the rotatable lifting device being formed at its lowest point with a gap adapted to cause the lifting device to fail to engage some of the warp carriers with shorter bent lower ends, and means for gradually closing the said gap and thereby progressively increasing the number of warp threads participating in the weaving operation. 55

4. A circular loom for the continuous and automatic manufacture of hats and hat-like articles, comprising an outer ring of stationary warp carriers having their lower ends bent, a slowly and intermittently revolving inner ring of warp carriers having their lower ends bent, the bent portions at the lower ends of different warp carriers being of different lengths, a rotatable lifting device adapted to engage with the bent lower ends of the warp carriers and thereby to raise the said warp carriers out of their lowest position for the formation of the shed, the warp threads from the moving warp carriers being laid spirally and the warp threads from the stationary warp carriers being laid radially, the rotatable lifting device being formed at its lowest point with a gap adapted to cause the lifting device to fail to engage some of the warp carriers with shorter bent lower ends, and means for gradually closing the said gap and thereby progressively increasing the number of warp threads participating in the weaving operation. 60

5. A circular loom for the continuous and automatic manufacture of hats and hat-like articles, comprising warp carriers having their lower ends bent, the bent portions at the lower ends of different warp carriers being of different lengths, a rotatable lifting device adapted to engage with the bent lower ends of the warp carriers and thereby to raise the said warp carriers out of their lowest position for the formation of the shed, the rotatable lifting device being formed at its lowest point with a gap adapted to cause the lifting device to fail to engage some of the warp carriers with shorter bent lower ends, means for gradually closing the said gap and thereby progressively increasing the number of warp threads participating in the weaving operation. 65

6. A circular loom for the continuous and automatic manufacture of hats and hat-like articles, comprising warp carriers having 70

- their lower ends bent, the bent portions at the lower ends of different warp carriers being of different lengths, a rotatable lifting device adapted to engage with the bent lower ends of the warp carriers and thereby to raise the said warp carriers out of their lowest position for the formation of the shed, the rotatable lifting device being formed at its lowest point with a gap adapted to cause the lifting device to fail to engage some of the warp carriers with shorter bent lower ends, means for gradually closing the said gap and thereby progressively increasing the number of warp threads participating in the weaving operation, a ring of columns, a roller rotatably mounted at the top of each column to form a circular roller track, a shuttle resting upon the said roller track, and a tongs-like device adapted to follow the outline of the article that is being woven and to gather together all the warp threads when one article is completed for the commencement of another article without the threads having to be cut and tied again.
7. A circular loom for the continuous and automatic manufacture of hats and hat-like articles, comprising an outer ring of stationary warp carriers having their lower ends bent, a slowly and intermittently revolving inner ring of warp carriers having their lower ends bent, the bent portions at the lower ends of different warp carriers being of different lengths, a rotatable lifting device adapted to engage with the bent lower ends of the warp carriers and thereby to raise the said warp carriers out of their lowest position for the formation of the shed, the warp threads from the moving warp carriers being laid spirally and the warp threads from the stationary warp carriers being laid radially, the rotatable lifting device being formed at its lowest point with a gap adapted to cause the lifting device to fail to engage some of the warp carriers with shorter bent lower ends, means for gradually closing the said gap and thereby progressively increasing the number of warp threads participating in the weaving operation, a ring of columns, a roller rotatably mounted at the top of each column to form a circular roller track, a shuttle resting upon the said roller track, a tongs-like device adapted to follow the outline of the articles that are being woven and to gather together all the warp threads when one article is completed for the commencement of another article without the threads having to be cut and tied again, and a conveyor device adapted to grip on both sides a chain of unseparated articles manufactured on the loom and remove them.
8. A circular loom for the continuous and automatic manufacture of hats and hat-like articles, comprising warp carriers having their lower ends bent, the bent portions at the lower ends of different warp carriers being of different lengths, a rotatable lifting device adapted to engage with the bent lower ends of the warp carriers and thereby to raise the said warp carriers out of their lowest position for the formation of the shed, the warp threads from the moving warp carriers being laid spirally and the warp threads from the stationary warp carriers being laid radially, the rotatable lifting device being formed at its lowest point with a gap adapted to cause the lifting device to fail to engage some of the warp carriers with shorter bent lower ends, means for gradually closing the said gap and thereby progressively increasing the number of warp threads participating in the weaving operation, a ring of columns, a roller rotatably mounted at the top of each column to form a circular roller track, a shuttle resting upon the said roller track, a tongs-like device adapted to follow the outline of the article that is being woven and to gather together all the warp threads when one article is completed for the commencement of another article without the threads having to be cut and tied again, and a conveyor device adapted to grip on both sides a chain of unseparated articles manufactured on the loom and remove them.

raise the said warp carriers out of their lowest position for the formation of the shed, the rotatable lifting device being formed at its lowest point with a gap adapted to cause the lifting device to fail to engage some of the warp carriers with shorter bent lower ends, means for gradually closing the said gap and thereby progressively increasing the number of warp threads participating in the weaving operation, and a conveyor device adapted to grip on both sides a chain of unseparated articles manufactured on the loom and remove them.

9. A circular loom for the continuous and automatic manufacture of hats and hat-like articles, comprising an outer ring of stationary warp carriers having their lower ends bent, a slowly and intermittently revolving inner ring of warp carriers having their lower ends bent, the bent portions at the lower ends of different warp carriers being of different lengths, a rotatable lifting device adapted to engage with the bent lower ends of the warp carriers and thereby to raise the said warp carriers out of their lowest position for the formation of the shed, the warp threads from the moving warp carriers being laid spirally and the warp threads from the stationary warp carriers being laid radially, the rotatable lifting device being formed at its lowest point with a gap adapted to cause the lifting device to fail to engage some of the warp carriers with shorter bent lower ends, means for gradually closing the said gap and thereby progressively increasing the number of warp threads participating in the weaving operation, a ring of columns, a roller rotatably mounted at the top of each column to form a circular roller track, a shuttle resting upon the said roller track, a tongs-like device adapted to follow the outline of the articles that are being woven and to gather together all the warp threads when one article is completed for the commencement of another article without the threads having to be cut and tied again, and a conveyor device adapted to grip on both sides a chain of unseparated articles manufactured on the loom and remove them.

In testimony whereof I have affixed my signature.

HEINRICH WISMER.
